UNITED STATES PATENT OFFICE.

MARION A. SAVAGE, OF SCOTIA, NEW YORK, ASSIGNOR TO GENERAL ELECTRIC COMPANY, A CORPORATION OF NEW YORK.

WINDING FOR ALTERNATING-CURRENT APPARATUS.

Application filed December 29, 1925. Serial No. 78,209.

My invention relates to electrical apparatus, and more particularly to the windings of alternating current apparatus.

In large alternating current generators in which the windings, which are disposed in the armature slots, consist of conductors of considerable depth, the magnetic flux across the slots due to the current in the conductors gives rise to parasitic voltages in the conductors which induce eddy currents therein. These currents if of sufficient magnitude may produce objectionable heating of the winding and cause the material of the conductor to be inefficiently utilized.

In such a machine, where each armature slot is filled with several conductors arranged one above the other, the flux due to current carried by the bottom conductor has a path partly through the iron core and partly through the space between the side walls of the slot. The distribution of this flux for convenience may be regarded as uniform from the top of the conductor to the mouth of the slot. Likewise the flux due to current carried by the second conductor from the bottom also may be regarded as evenly distributed in the space between the slot walls from the top of that conductor to the mouth of the slot and similarly for the remaining conductors in the slot. The total flux density in the slot therefore is not uniform but increases from the top of the bottom conductor to the mouth of the slot. In the above, consideration has been given only to the flux between the top of a conductor and the mouth of the slot. Current in each conductor produces a flux throughout the depth of the conductor which flux increases from the bottom to the top of the conductor and produces a voltage in the conductor which increases from the bottom of the conductor to the top thereof in approximately a parabolic manner. The total voltage in any half turn of a coil is thus made up of a voltage due to the flux of that half turn of the coil plus the voltage due to the flux from the other half turns of the coil below the one in question. This voltage varies in magnitude for each half turn, being greatest for that half turn at the top of the slot. The voltages induced in the two sides of the coil are in opposite senses due to the fact that the reversing end turn of the winding inverts one side of the coil

relative to the other side. As a result of this reversal the difference of voltages induced in the top and the bottom portions of the conductor in one side of the coil is partly neutralized by that in the other side of the coil. But, because of the unequal distribution of flux throughout the depth of the slot as pointed out above there still remains a voltage difference between the top and the bottom portions of the conductor which gives rise to objectionable eddy currents through the conductor forming the winding.

As a means of reducing these eddy current losses it has been proposed to use a stranded conductor and to twist the part of the conductor which lies in the slot to vary the relative position of the various strands. Such a winding has the serious objections of increased cost of manufacture due to the use of special tools and greater labor as well as to the necessity of greater slot depth. It has also been proposed to divide the strands of each conductor into two or more groups and to carry these separate groups through several coils with proper transposition before finally clipping them altogether. This method has the objection of requiring fairly complicated cross connections at the clips and of giving a considerably high voltage between strands.

It is an object of my invention to provide an improved winding wherein the eddy current losses are reduced to a relatively low value by giving to the stranded conductor forming the winding, twists arranged in the portions of the winding which lie outside of and which connect the portions thereof which lie in the slots. In the specific form of my invention illustrated, I form the winding of coils constructed in the customary manner and having the usual terminal connections and in these terminal connections I give the conductor a twist of substantially 180 degrees. Each two adjacent coils joined by such terminal connections thus will have the eddy currents of one coil opposing the eddy currents of the other. Since the coils are opposed to each other in pairs the conductor may be twisted in only alternate terminal connections, the remaining terminal connections having the usual form.

My invention will be better understood from the following description taken in co-

nection with the accompanying drawing, and its scope will be pointed out in the appended claims.

In the drawing, Fig. 1 shows two adjacent coils of a winding with terminal connections illustrating one embodiment of my invention; Fig. 2 is a cross section of the coils of Fig. 1 on line 2—2 showing them in their respective core slots; Fig. 3 is a detail of the type of terminal connection shown in Fig. 1; and Figs. 4 and 5 are similar details of modified forms of terminal connections embodying my invention.

The two coils 1 and 2 of Figs. 1 and 2 are shown as three-turn coils, the left hand sides of coils 1 and 2 occupying the bottoms of slots 3 and 4 respectively and the right hand sides of these coils occupying the tops of slots 5 and 6 respectively. In Figs. 1 and 3 I have shown the upper terminal lead 7 of each coil twisted through 180° and connected to the lower terminal lead 9 of the next coil by an insulating clip 10. The conductor forming the coils is shown as comprising four individually insulated double strands and the clip 10 as comprising four separate insulated connectors 11 which serve to electrically connect the double strands in pairs as shown while maintaining the respective strands insulated from each other.

In order that the effect of the twist 8 may be more readily seen I have shown one double strand shaded throughout the two coils. Thus in slot 3 the shaded strand of coil 1 is at the bottom of the conductor and in slot 5 the shaded strand is at the top of the conductor due to the effect of the rear reversing end turn 12. In slot 4 the shaded strand again is at the top because the conductor has undergone two reversals, one at the front reversing end turn 13 and the other at the twist 8. The shaded strand in slot 6 is again opposite to that in slot 4 due to the rear reversing end turn 14. It will be seen therefore that the voltage difference induced in the strands of one coil tending to cause eddy currents to circulate therein is neutralized by an equal and opposite voltage difference induced in the next adjacent coil.

Due, however, to the small difference in time phase of the parasitic voltages in two coils when these coils share their slots with coils of different phases the eddy currents may not be reduced to zero, but in such a case the reduction is material and the resulting voltage is so low that the losses are small.

In Fig. 4, I have shown coil terminals 15 and 16 corresponding to terminals 7 and 9 each having a 90° twist at points 17 and 18 by which the same object is accomplished as by the single 180° twist shown in Fig. 3.

It may prove advantageous at times to make the twist in the loop connection be-

tween the coils at the clip and such an arrangement is shown in Fig. 5. Here as in Figs. 3 and 4, the strands are insulated from each other at the clip, but to simplify the drawing no insulation has been shown. By 70 the connectors 19 and 20, the top and bottom strands of one coil terminal are connected to the respective top and bottom strands of another coil terminal, thus securing the same effect as those connections 75 shown in Figs. 3 and 4. In general the middle two or three strands may be solidly clipped together, as shown at 21, without causing much additional loss, and such an arrangement is resorted to in Fig. 5 to simplify 80 the clip structure. It is to be understood that this same expedient may be used in connections such as shown in Figs. 3 and 4.

Since the coils are balanced against each other in pairs each alternate connecting clip may, if desired, be made solid in which case the strands are not insulated from each other but all electrically connected together. In practice, however, the existence of odd 85 numbers of slots in some phase belts, the desirability of keeping the pole connection clips solid, and of preserving uniformity in all the coils results in the use of the special method of clipping in all the connections between the coils. This gives a large factor of safety since every other clip can be short circuited without increasing the losses.

It will thus be seen that I have provided a simple and non-expensive means of accomplishing the desired result of eliminating eddy current losses in coil windings. Also by my method I avoid excessive voltages between strands and secure all the advantages incident to the use of form-wound coils.

What I claim as new and desire to secure by Letters Patent of the United States, is:

1. A winding for alternating current apparatus comprising slot embedded portions and other portions connecting said portions, said windings being formed of a conductor having a plurality of insulated strands and having means for reducing eddy current losses therein comprising twists of substantially 110 180 degrees in the conductor arranged 115 in said connecting portions.

2. A winding for alternating current apparatus comprising a plurality of coils formed of a conductor having insulated strands, the top and bottom strands of one coil terminal being connected in series with the respective top and bottom strands of another coil terminal and insulated from adjacent strands whereby the voltage difference induced in the strands of the conductor of one coil is substantially neutralized by the voltage difference induced in the strands of the conductor in the other coil.

3. A winding comprising a plurality of coils each formed of a conductor consisting 130

of strands insulated throughout the coil, and means for connecting and insulating strands of one coil in series with strands of another coil which are reversed in order relative to the axis of the conductor.

4. A winding comprising a plurality of coils having reversing end turns and formed of conductors comprising insulated strands, and means connecting the strands of one coil terminal with the respective strands of another coil terminal while maintaining the respective strands insulated from each other, said means including conductors in the form of a loop in which the order of the strands is reversed, the conductor comprising said loop being twisted substantially 180 degrees.

5. A winding for a dynamo-electric machine comprising a plurality of coils each having reversing end turns and formed of conductors comprising a plurality of insulated strands, and means comprising insulated connectors for connecting the strands

of the terminal of one coil in series with the respective strands of the terminal of another coil, said connected terminals forming a reversing loop and one of said terminals having a twist of substantially 180 degrees therein.

6. A winding for dynamo-electric machines comprising a pair of adjacent coils, each having a reversing end turn at each end thereof and being formed of conductors comprising a plurality of insulated strands, and a connecting clip comprising separate insulated connectors for connecting the strands of the terminal of one coil in series with the respective strands of the terminal of the adjacent coil, said connected terminals forming a reversing loop and one of said terminals having a twist therein of substantially 180 degrees.

In witness whereof, I have hereunto set my hand this 24th day of December, 1925.

MARION A. SAVAGE.
